UNITED STATES PATENT OFFICE.

LAWRENCE ANTHONY COSTELLO, OF WASHINGTON, DISTRICT OF COLUMBIA.

BATTERY-REPAIR TOOL.

Application filed June 25, 1923. Serial No. 647,544.

This invention has reference to battery repair work and more particularly to means for accomplishing such work in a more economical manner than heretofore.

5 The principal object of the invention is to provide a cutting tool for severing the connector straps from the binding posts of the cells of a battery in an efficient manner and with a saving of both time, labor, and material, the severing being effected in such manner as to enable the same connector straps to be used again, if desired, when reconnecting the cells.

10 A further and additional object is to provide a battery repair tool of new and novel design, capable of being manufactured at little cost and readily adapted to fit in a suitable holder, the said tool having both a boring and a cutting action.

20 Various other objects and advantages of the invention will be apparent from the following description.

In the drawing:

25 Figure 1 is an end elevation of the tool, showing the cutters edgewise,

Figure 2 is a similar view of the tool, showing the cutters sideways.

Figure 3 is a perspective view of the tool in inverted position, and

30 Figure 4 is a plan view of two battery cells showing the manner of severing the connector strap from the post of one cell.

In the drawings, 10 and 11 indicate adjacent cells of a battery which are connected by a strap 12. This strap, which is generally of lead, is provided at each end with a cap 13 which engages over one of the terminal posts 14 of a cell, the said posts being also of lead and united with the cap by heating, welding, or otherwise. This provides an integral connecting structure between adjacent cells which must be severed to permit separation of the cells when the latter are to be repaired. The usual practice followed, in effecting the separation of the cells, is to cut thru the connector strap by boring or drilling a hole thru the cap and the underlying post. This method, however, results in a great waste of material since a new strap must be substituted for the severed one and, in addition, the post must be built up again as the utility of the same is destroyed by the drilling operation.

55 However, by employing a cutting tool such as provided by the present invention

this waste of material is not only avoided but the time required to reconnect the cells of a battery is shortened, thereby materially decreasing the labor and hence, the cost, of the repair work. The tool comprises essentially a cutter head 15 which may be circular in form and which is provided with an integral taper shank 16 adapted to be received in the holder of a drilling machine or a drill brace. Projecting centrally from the cutter head is an auger or drill bit 17 as shown and on each side of the bit in spaced parallel relation thereto are side cutter-bars 18 and 19, respectively, which have longitudinal cutting edges 20 provided at relatively opposite sides. Extending crosswise of the face of the cutter head, on opposite sides of the center bit and aligning with each other are horizontal cutters 21 which project laterally beyond the cutting head on opposite sides as shown at 22. To provide clearance for the cutting edges of the horizontal cutters, the face of the cutters is provided with sloping cutouts 23.

In practice, the tool is disposed over strap 12 at one end with the center bit 17 coinciding with the center of a post 14, with the point 24 of the bit resting on cap 13. The bit is of such length that the point is beyond the outer ends of cutter bars 18, the latter coming in contact with the cap after the point of the bit has penetrated the same. Hence, the drill when rapidly rotated, will bore a hole 25 centrally thru the cap and the post while cutters 18 will cut a circular path 26 in the cap and around the post as shown to advantage in Figure 4. As the bit is advanced into the post the horizontal cutters 21 will engage the top of the cap, cutting the same away and facing off the surface of the post in a manner that is self evident.

It will therefore be seen that cutters 18 completely sever the cap from the post without destroying the connector strap, the longitudinal cutting edges of the said cutter serving to trim the sides of the post while the horizontal cutters serve to trim and face off the top of the post and cap. It is obvious that the cutting of a circular slot in the cap provides the latter with a ring or loop which is easily engaged or disengaged with the post and hence, after severance, the strap is still capable of being used. The facing or smoothing of the severed parts by the

facing cutters 21 enables them to be readily united together by heating, welding, or otherwise.

From the foregoing it is thought that the advantages of the invention will be readily understood and that further detailed description thereof is not required.

What is claimed is:

1. A battery tool including a cutter head, 10 a centrally projecting boring bit carried by said head, a cutter bar projecting from the head in spaced relation to the boring bit to produce a circular cut, and a straight edged facing cutter carried by said head

and extending from the boring bit to a point 15 outwardly of the cutter bar, whereby to produce a facing cut over a circular area exceeding the diameter of cut of the cutter bar.

2. A battery tool as claimed in claim 1, characterized by the provision of two of said 20 cutter bars and two of said facing cutters, said cutter bars being arranged on opposite sides of the boring bit, and said facing cutters being arranged on said head intermediate the cutter bars. 25

In testimony whereof I affix my signature.

LAWRENCE ANTHONY COSTELLO.
